UNITED STATES PATENT OFFICE.

HORACE WARREN PARSONS, OF WAMEGO, KANSAS.

CHURN.

SPECIFICATION forming part of Letters Patent No. 439,549, dated October 28, 1890.

Application filed December 17, 1889. Serial No. 334,073. (No model.)

To all whom it may concern:

Be it known that I, HORACE WARREN PARSONS, a citizen of the United States, residing at Wamego, in the county of Pottawatomie 5 and State of Kansas, have invented certain new and useful Improvements in Churns; and I do declare the following to be a full, clear, and exact description of the invention, such as will enable others skilled in the art to which 10 it appertains to make and use the same.

My invention relates to certain new and useful improvements in churning, the nature of which will be understood from the following description when taken in connection with 15 the accompanying drawings, in which—

Figure 1 is a vertical section, and Fig. 2 a detail plan.

In the drawings, A represents a can which forms the outer wall of the churn, and B the 20 churn proper.

Churn B is provided on its lower end with an extended base B', which fits snugly within the can A and serves to hold part B in the center of can A, a space being left between 25 parts A and B, as shown. The top of base B' is perforated, as at a, and the space between parts A and B being filled with water the water will pass through such perforations and thus circulate around the sides and bottom 30 of the churn.

C C represent bands surrounding can A and provided with eyelets through which vertical rods D D are passed, and by which such rods are supported. These rods extend a 35 suitable distance above the top of the can and churn proper, and at their upper ends are arranged to telescope with hollow rods E, each rod D being provided with a nut b adjustably mounted thereon, such nuts serving 40 to support rods E and render the vertical adjustment of such rods possible. At their upper ends the rods E are provided each with a bearing c, in which a shaft F rotates. Mounted upon shaft F is a hand-wheel G and 45 a friction-wheel H, the latter consisting of a disk provided on both faces near its periphery with a holding-surface d.

I I are the paddle-shafts, and J the paddles. At points near their upper ends each shaft carries a friction-wheel K, each of which consists of a wheel grooved on its periphery and provided with packing e. Shafts I have bearings at their lower ends in the bottom of part B and at their upper ends in supports L, such supports being adjustably mounted upon a 55 bar M by means of pins f and set-screws g, the latter entering slots h in bar M. This bar is also provided with openings i to permit of the passage therethrough of rods D and E, and with notches j for shafts I I, 60 notches being provided in the last-named instance to admit of the removal of the paddle-shafts without displacing the friction-wheels. Each rod E is provided with two nuts l, between which bar M is placed. 65

The operation will be readily understood, motion being imparted to the paddles through the line of gearing described, and the vertical adjustment of the parts being provided for.

The outer casing A is preferably provided 70 with an opening m at its lower end, through which the water may be drawn off. A thermometer N may also be provided in order that the temperature may be taken, such device being secured to the churn B. 75

What I claim is—

The combination of the can, the rods D, secured thereto, the rods E, secured on the upper ends of the rods D and adjustable vertically thereon, the bar M, adjustably secured 80 on the rods E, the paddle-shafts supported by the bar M, the driving-shafts journaled in the upper ends of the rods E, and gearing between the said driving-shaft and the paddle-shafts, as set forth. 85

In testimony whereof I affix my signature in presence of two witnesses.

HORACE WARREN PARSONS.
